UNITED STATES PATENT OFFICE.

EDWIN A. PERKINS, OF NEW YORK, N. Y.

RECIPROCATING ENGINE.

BEST AVAILABLE COPY

1,082,902.

Specification of Letters Patent. Patented Dec. 30, 1913.

Application filed September 14, 1911. Serial No. 649,365.

To all whom it may concern:

Be it known that I, EDWIN A. PERKINS, of New York, in the county and State of New York, a citizen of the United States, have invented a new and useful Improvement in Reciprocating Engines, of which the following is a full, clear, and exact description, reference being had to the accompanying drawings, forming a part of this specification, in explaining its nature.

My invention relates to a reciprocating engine or drill of that valveless type having reciprocating pistons connected with one another and reciprocated by the admission of fluid pressure thereto.

It is among the objects of my invention to provide an engine or drill of the above character with an arrangement whereby the pistons may be alternately impelled and reciprocated, or, in other words, reciprocated by the admission of pressure directly to the inside ends of the pistons themselves, thereby eliminating strain from the piston rod by the application of power directly to the pistons instead of indirectly through said rod; to provide also a construction in which the pistons and connecting rod will have a relatively long, properly balanced stroke and this essentially by preventing a leakage of fluid pressure between the respective chambers containing the pistons and which might otherwise occur around the piston rod passing through a partition or diaphragm interposed between said chambers; to effect a closure between said chambers around the piston rod at the point of said partition or diaphragm by means which will compensate for wear at this point; to provide an improved form of metallic packing for effecting such closure; and to provide also an engine or drill of such construction or such assemblage of parts as can be easily made.

My invention can best be seen and understood by reference to the drawings in which it is shown in the form of a rock drill or such portion thereof as is necessary to a proper understanding of the working parts.

Figure 1 shows the drill in vertical cross section. Fig. 2 is a section on the line 2—2 of Fig. 1. Fig. 3 is a section on the line 3—3 of Fig. 1. Fig. 4 is a section on the line 4—4 of Fig. 1. Fig. 5 is a plan of a portion or part of the drill to which special reference will hereinafter be made. Fig. 6 is a section on the line 6—6 of Fig. 5. Fig. 7 is a perspective showing the metallic packing

to which reference will hereinafter be made, while Figs. 8 and 9 show in perspective the instrument or means which assists in the retention of such packing.

Referring to the drawings:—1 represents the handle and 2 the barrel or body of the drill. The body 2 is made sectional in character, consisting of the sections or parts 3 and 4, respectively, and of which the section 4 is secured to the section 3 by an outwardly-disposed, interiorly-threaded inner end portion 5 which screws onto the inner exteriorly-threaded end portion of the section 3.

Formed within the respective sections or parts comprising the body of the drill are cylindrical chambers 6 and 7, respectively. Contained within these respective chambers to reciprocate therein are pistons 8 and 9, respectively. Of these pistons the piston 8, which reciprocates within the chamber 6, is smaller in diameter than the piston or hammer 9 reciprocating within the chamber 7. The pistons are connected to move both in the same direction by a piston rod 10.

The piston-containing chambers 6 and 7 are separated from one another by what may be termed a diaphragm or partition 11 through which the piston rod extends. This diaphragm apart from separating the two chambers contains also as will hereinafter be explained, a metallic packing engaging the piston rod to form a closed joint around said rod between said chambers.

According to the construction shown the diaphragm or partition 11 forms a separate and independent part from the sections or parts 3 and 4 which form the body of the drill. The diaphragm is located within the inner end portion of the section 4 of the drill and between it and the section 4, the diaphragm being held by and between said sections on bringing the same together. The body of the diaphragm consists of a short cylindrical portion 12 which is the part held between the sections 3 and 4 as above explained. The body 12 has a bore or opening considerably larger than the piston rod which extends through it. On the outside it is provided (as may be seen by reference to Figs. 5 and 6) with a series of wings 13 preferably quadrangularly arranged and which bear laterally against the interior end portion of the section 3 of the body of the drill within which the diaphragm is contained.

At its opposite ends the body 12 of the diaphragm when held as aforesaid, en-

gages the respective sections 3 and 4 in those parts forming the inner ends of their respective cylindrical chambers. In order to provide tight joints at these points the body of the diaphragm is preferably socketed within the ends of the respective sections, the engaging parts being provided with beveled or inclined meeting edges 14.

As was above explained the interior face 10 of the body of the diaphragm is some little distance removed from the piston rod leaving an annular chamber or box 15 between said parts. The bottom end of this chamber is closed by an annular edge portion 16 which extends inwardly in the direction of and to the piston rod from the bottom end of said body 12 of the diaphragm. The top end of this chamber is closed as shown by a ring 17 which is threaded to fit into the top end of said body 12 and fills the space between the top end of said body and the piston rod. Both the edge portion 16 and the ring 17 are provided with annular lips 18 which extend inwardly toward one another 25 alongside the piston rod and form flanges which assist in the retention of packing 19 contained within the chamber or box formed within the diaphragm and located around the piston rod between the ends of said lips 30 18 which act to hold the same in place as against longitudinal displacement.

The packing 19 may consist of any suitable metallic packing which may fit snugly around the piston rod and be capable of taking up wear. In Fig. 7 there is shown a type or form of packing which I prefer to employ. This consists of an expandable and contractible metal tube or cylinder comprising a number of curved sections 20 which 40 lap by one another to form broken transverse joints. Wrapped around this packing and over the annular lips 18 of the diaphragm is a covering 21 of some yielding material preferably a fibrous material such as leather. There is then applied to the packing and covering 21 a retaining spring clip 22. I prefer to employ a tubular clip having overlapping ends substantially like that shown in Fig. 9. The packing and 45 means for retaining the same do not entirely fill the chamber or box of the diaphragm for at the rear of the clip 22 there is left an annular fluid pressure space or compartment in communication with the 50 chamber 6 of the drill by way of openings 55 23 formed through the ring 17 which closes the upper end of said chamber 15.

Referring now to that part of the drill 50 which relates to the admission and expulsion of the fluid pressure which reciprocates the respective pistons for alternately impelling and retracting the same, attention is first directed to the fluid inlet opening 24

municating with this port is a passage 25 formed in the wall of said section 3 and which extends downwardly and thence inwardly to communicate with the cylindrical chamber 6, containing the piston 8, at a point near the bottom end of the chamber below said piston or so that it will constantly act upon the inner end of said piston.

Communication is had between the cylindrical chambers 6 and 7 of the drill or so 75 that the pressure may act upon the inside end of the piston or hammer 9 by means of grooves or slots 26 formed in the piston rod. The fluid pressure admitted to the chamber 6 will enter these slots and thence pass 80 downwardly through the same to enter the chamber 7 and engage the inner or rear end of the piston 9.

In the wall of the section 3 of the drill around the chamber 6 therein there is 85 formed a circular compartment 27 which extends from a point adjacent the upper end of the chamber 6 to the diaphragm 11. The chamber 6 at the upper end thereof beyond the outer end of the piston 8 contained therein communicates with the opening or passage 27 by way of a port 28. The opening or passage 27 connects also with 90 openings 29 which are formed outside the diaphragm 11 and between it and the adjacent wall of the section 4 of the drill with 95 in which the diaphragm is contained, the outwardly-projecting wings 13 of the diaphragm assisting in the formation of such openings (see Fig. 3). The openings 29 communicate in turn with annular opening 100 or compartment 30 formed within the section 4 of the drill around the cylindrical chamber 7 therein (see Fig. 4). Communication is had between the interior of said 105 chamber 7 and the compartment 30 by way of ports or openings 31 and 32, respectively. The compartment 30 also communicates with the atmosphere by way of an outside 110 port or opening 33.

The operation of the drill is as follows:— The pressure constantly enters by way of the port 24 and passage 25 into the lower end of the chamber 6 and accordingly constantly acts upon the inner end of the piston 8 thereby tending to retract the piston rod and the pistons carried by it. When the piston 8 is occupying a retracted position and before it has arrived at its fully retracted position the pressure admitted to 115 the chamber 6 will have entered the grooves 26 formed in the piston rod and thereby be admitted to act upon the inner inside end of the piston or hammer 9 tending accordingly to effect an impulsion of this piston or hammer together with the piston rod and piston 8. This effect is obtained because the piston or hammer 9, as before explained, presents an inner face much larger 120

8. Accordingly though pressure is constantly being admitted to the chamber 6 to effect a retraction of the pistons, yet as long as the pressure is admitted to the chamber 5 be 7 to act upon the piston or hammer 9 therein it will overcome the retractive power upon the piston 8 and effect an overbalanced impulsion of the moving parts. This continues until the ends of the grooves 26 draw 10 into the packing when all communication is shut off between the grooves 26 and the chamber 6 and the pressure will have only a direct action upon the inner end of the piston 8 to effect a retraction of the parts. 15 Before such retraction occurs, however, the pressure will have moved the piston or hammer 9 and connecting parts to a point where the piston 9 will have moved beyond the ports 30 which communicate, as above explained, with the atmosphere with the effect that the fluid pressure admitted and expanding to act upon the piston 9 will be allowed to escape through the ports or openings 31 to the atmosphere and thereby allow 20 a proper retraction of the piston 9. In this same connection it will be explained that the relative arrangement of the grooves 26 and ports 31 is preferably such that the grooves 26 will be cut off from the chamber 25 before the piston or hammer 9 has passed the ports 31 in order that the pressure admitted to the piston or hammer 9 may be allowed to expand and the expanding pressure give a final impulsion to the piston and connecting parts for driving it beyond the ports 31 thereby tending to utilize to the best advantage the available power. As the pistons and connecting rod are moved upwardly by the pressure applied to the inner 35 end of the piston 8 it will of course be apparent that before the piston 8 has arrived at the limit of its upward stroke the pressure will again be admitted to the piston 9 thereby effecting a proper and orderly reciprocation of the moving parts. 40

No back pressure will be developed upon the piston 8 excepting such slight pressure as may assist in effecting its proper and orderly retraction for the reason that the chamber 6 at the rear of this piston connects through the port 28, compartments or passages 27, 29 and 30 and port 33 with the atmosphere. There will also be no pressure to impede or retard the proper impulsion of the piston or hammer 9 and connecting parts inasmuch as that portion of the chamber 7 forward of the piston or hammer 9, when in a retracted position, is open to the atmosphere through the ports 31, 32, 55 compartment 30 and outlet port 33.

As before explained, the pressure is constantly within the chamber 6 of the drill. The pressure being thus admitted thereto, it will accordingly pass from this chamber 60 through the said openings 23 in the ring

17 into the chamber 15 of the diaphragm in the rear of the metallic packing around the piston rod, the covering therefor and clip retaining the same and with the resultant effect of holding the covering for the packing tight over all the joints which it tends to cover and the packing itself snugly against the piston rod, thereby obtaining an absolutely tight joint at this point and preventing leakage of the fluid pressure around the piston rod between the two chambers of the engine. As the parts wear the pressure will compensate for or take up such wear thereby securing a tight joint at all times or until the packing is worn out when new 75 packing may be inserted.

In showing my invention as applied to a drill it will be understood, of course that such drill may be of the direct or indirect type or one in which the chisel (not shown) is either secured to the piston or hammer 9 or loosely arranged in the end of the body of the drill as is usual in such constructions. 80

Having thus fully described my invention, I claim and desire to secure by Letters 90 Patent of the United States:—

1. In an engine of the character specified, the combination of a body or casing having formed therein separate chambers with a partition or diaphragm separating said chambers, pistons located within said respective chambers one of which pistons is larger than the other, a piston rod connecting said pistons through said diaphragm, the said engine being provided also with a valveless 95 way through which fluid pressure may be constantly admitted to the inner end of the smaller one of said pistons and intermittently admitted to the inner end of the larger one of said pistons for effecting the 100 reciprocation thereof.

2. In an engine of the character specified, the combination of a body or casing having formed therein separate chambers with a partition or diaphragm separating said chambers, pistons located within said respective chambers one of which pistons is larger than the other, a piston rod connecting said pistons through said partition or diaphragm and having formed therein 110 grooves by which communication is had between said chambers when said pistons are in a retracted position, the said body or casing of the engine having also formed therein valveless inlet and exhaust passages by 115 which fluid pressure may be constantly admitted to the chamber containing the smaller one of said pistons and intermittently admitted through the grooves formed in said piston rod into the chamber containing the larger one of said pistons and outlet 120 therefrom as said pistons are reciprocated.

3. In an engine of the character specified, the combination of a body or casing having formed therein separate chambers with a 130

partition or diaphragm separating said chambers, pistons located within said respective chambers one of which pistons is larger than the other, a piston rod connecting said pistons through said partition or diaphragm, said piston rod having grooves formed therein to provide communication between said chambers when said pistons are in a retracted position, said body or casing having also formed therein a valveless fluid inlet passage communicating with the inner end of said chamber containing the smaller one of said pistons to have constant communication with the inner end of said smaller piston, said casing having also an outlet passage therein communicating with the outer end of the chamber containing the smaller one of said pistons and with the atmosphere, said casing having also valveless passages therein connecting with the atmosphere and with the chamber containing the larger one of said pistons at points beyond the outer end of said larger piston when in a retracted position.

25 4. In an engine of the character specified, the combination of a body or casing having formed therein separate chambers with a partition or diaphragm separating said chambers, pistons located within said respective chambers one of which pistons is larger than the other, a piston rod connecting said pistons through said partition and provided with a way by which communication is had between said chambers when said pistons are in a retracted position, said partition having also a packing chamber formed therein and one side of which is open to said piston rod and the rear side of which chamber is in open communication with the chamber containing the smaller of said pistons, a fluid-pressed packing arranged in the open side of said packing chamber around said piston rod, said casing having also a fluid inlet passage in constant communication with the chamber containing the smaller of said pistons, said casing having also an exhaust passage communicating with the chamber containing the other of said pistons.

30 35

piston and intermittently admitted through the said way provided in said piston rod into the chamber containing the larger of said pistons and to the inner end of said larger piston, said engine having also an exhaust passage by which the fluid pressure may escape from the chamber containing said larger piston as said pistons are reciprocated.

5. In an engine of the character specified, the combination of a body or casing having formed therein separate chambers with a partition or diaphragm separating said chambers, pistons located within said respective chambers one of which pistons is larger than the other, a piston rod connecting said pistons through said partition and provided with a way by which communication is had between said chambers when said pistons are in a retracted position, said partition having also a packing chamber formed therein and one side of which is open to said piston rod and the rear side of which chamber is in open communication with the chamber containing the smaller of said pistons, a fluid-pressed packing arranged in the open side of said packing chamber around said piston rod, said casing having also a fluid inlet passage in constant communication with the chamber containing the smaller of said pistons, said casing having also an exhaust passage communicating with the chamber containing the other of said pistons.
